UNITED STATES PATENT OFFICE.

CHARLES CRETORS, OF CHICAGO, ILLINOIS.

DESIGN FOR A VEHICLE-TOP.

No. 38,042.

Specification for Design.

Patented May 29, 1906.

Application filed April 5, 1906. Serial No. 310,177. Term of patent 14 years.

To all whom it may concern:

Be it known that I, CHARLES CRETORS, a citizen of the United States of America, residing at Chicago, in the county of Cook and State of Illinois, have invented a new, original, and ornamental Design for Vehicle-Tops, of which the following is a specification, reference being had to the accompanying drawings, forming a part thereof, and in which—

top, showing my new design. Fig. 2 is a side view, and Fig. 3 is a plan view, of the same.

I claim—

The ornamental design for a vehicle-top, as shown.

CHAS. CRETORS.
